PAIR OF SUN GLASSES OR THE LIKE

Finn H. Magnus, Washington Valley Road,
Morristown, N.J.

Filed Apr. 20, 1962, Ser. No. 69,783

Term of patent 14 years

(Cl. D57—1)

FIG. 1 is a front elevational view of a pair of sun glasses or the like showing my new design;

FIG. 2 is a top plan view thereof;

FIG. 3 is a rear elevational view thereof; and

FIG. 4 is a side elevational view thereof.

The temples are shown broken away in FIG. 2 for convenience of illustration.

The dominant features of my design reside in the portions shown in full lines.

I claim:

The ornamental design for a pair of sun glasses or the like, substantially as shown and described.
